UNITED STATES PATENT OFFICE.

JOSEPH FOSSEL, OF FARNUMSVILLE, MASSACHUSETTS.

MACHINE FOR MAKING, CHARGING, AND SEALING CARTONS.

1,306,422.

Specification of Letters Patent. Patented June 10, 1919.

Application filed July 24, 1916. Serial No. 110,860.

To all whom it may concern:

Be it known that I, JOSEPH FOSSEL, a citizen of the United States, residing at Farnumsville, in the county of Worcester and State of Massachusetts, have invented new and useful Improvements in Machines for Making, Charging, and Sealing Cartons, of which the following is a specification.

The object of the present invention is to provide an improved machine for making, charging, closing, and sealing, cartons. The invention is embodied in a plurality of mechanisms that are organized to coöperate with each other automatically in such manner that no human agency is called into service from the time the flat cardboard blanks are placed in stack-forming relation upon the primary feed-table, until after the formed, charged, closed, and sealed cartons are delivered out of the machine.

The charging mechanism is controlled by the carton-forming mechanism through the agency of the cartons themselves, in such manner that there will be no delivery of charging material unless there is a carton in position to receive it. This control of the charging mechanism avoids waste of charging material if, for example, there should be an omission of one or more cartons from the series of cartons undergoing the process of being formed, or if the driving of the machine should continue after the supply of cartons was exhausted.

The foregoing brief outline of the invention is sufficient to give a general idea of the fundamentals, but the details of the mechanisms, and the relation and coöperation of the latter, are hereinafter fully described with reference to the accompanying drawings. It may be explained at this time that some of the elements have been omitted purposely from the general views of the drawings, especially Figures 1, 2 and 3, to avoid confusion. This is because of the great reduction in the scale of the drawings, necessary to enable the general views to be made within the prescribed limits. However, the elements that are omitted as aforesaid are illustrated in special figures of the drawings, and references are made to them to indicate their intended relation to the other elements with which they coöperate.

Of the accompanying drawings that form a part of this application:

Fig. 1 represents an elevation of the machine, being a general view wherein the blank-feeding mechanism is at the right, the charging mechanism in the middle, and the delivery end at the left.

Fig. 2 represents an end elevation of the right-hand end of the machine with reference to Fig. 1, the blank-feeding mechanism being at the left, the carton-forming mechanism being in the middle, and the charging mechanism being at the top.

Fig. 3 represents a top plan view of the machine,—some of the elements being omitted as aforesaid, and a portion of the blank-feeding mechanism being broken away at the bottom of the figure. According to this view, the carton blanks are fed, first, from right to left (from A to B), then from bottom to top (from B to C), then from right to left (from C to D), the cartons being fully formed but open at one end for charging, thence the charged cartons move from D to F through a semicircular path in a clockwise direction, with one intermediate position of dwell, and are delivered from the left-hand end of the machine, in line with arrow F.

Fig. 4 represents a vertical section, on a larger scale, through the magazine in which the carton blanks are stored in stack-forming relation and from which they are fed one by one from right to left. The plane of this section is indicated in a general way by line 4—4 of Fig. 2.

Fig. 4^a represents a face view of a cardboard blank from which a carton can be made, charged, closed and sealed by the present machine. This blank is suitably slitted and scored prior to undergoing the process performed by the present machine. A duplicate of this figure is shown on another sheet bearing figures hereinafter described.

Fig. 5 represents a top plan view of that portion of the magazine that is broken away from the lower part of Fig. 3, the scale of Fig. 5 being the same as that of Fig. 4.

Fig. 6 represents a sectional view, similar to Fig. 4, of the lower elements of the magazine, but the movable bottom is at its left-

hand extreme in Fig. 6, whereas in Fig. 4 it is shown at the right-hand extreme.

Fig. 7 represents a vertical section through the blank-feeding mechanism and paste-applying mechanism intersected by line 7—7 of Fig. 1, the scale of Fig. 7 being about twice as great as that of Fig. 1. The point of view of Fig. 7 corresponds to that of Fig. 2.

Fig. 8 represents a top plan view of a portion of the paste-applying mechanism included in Fig. 7.

Fig. 9 represents an elevation, partly in section, of the paste-applying device shown in Fig. 7, in the first stage of its operation upon a carton blank.

Fig. 10 represents a view similar to Fig. 9, showing the paste-applying device in a more advanced position.

Fig. 11 represents a vertical section, somewhat diagrammatic, through the blank-forming mechanism intersected by line 11—11 of Fig. 3.

Fig. 12 represents a sectional view, similar to Fig. 11, of some of the carton-forming elements included in the latter figure, the carton being in a more advanced stage of formation in Fig. 12.

Fig. 13 is a sectional view, similar to Fig. 12, showing the mechanism that operates one of the carton-forming devices.

Fig. 14 is a view similar to Fig. 11 excepting that it omits some of the carton-forming devices and includes a pressure device by which the lapped portions of the carton are pressed one upon another to cause the paste on one of them to adhere to the other.

Fig. 15 is a view similar to Fig. 14, showing the pressure device in coöperative relation to a carton-forming core.

Fig. 16 represents an elevation, partly in section, of the devices that fold the flaps at one end of the carton to close the bottom of the latter.

Fig. 16^a represents a horizontal section of a carton before its end flaps have been folded by the devices shown in Fig. 16. This figure represents the condition of the carton at the position indicated by line 16^a—16^a of Fig. 16, and includes the core on which the carton is formed.

Fig. 16^b represents a sectional view through a carton at the position indicated by line 16^b—16^b of Fig. 16, and includes the core on which the carton is being formed.

Fig. 16^c represents a view similar to Fig. 16^b, showing a carton undergoing the flap-folding operation next after that shown by Fig. 16^b.

Fig. 17 represents a view similar to Fig. 16, showing two of the carton cores at positions of dwell.

Fig. 17^a represents a sectional view in a horizontal plane (see line 17^a—17^a of Fig.

17) through a carton that has had one of its end flaps folded in against the end of the core.

Fig. 18 represents a view similar to Fig. 17 excepting that the movable flap-folding device is in flap-folding position.

Fig. 18^a represents a sectional view in a horizontal plane (see line 18^a—18^a of Fig. 18) through the carton intersected by said line, showing the two flap-folding devices folding two of the flaps against the end of the core.

Fig. 19 represents a top plan view including the flap-folding devices shown by Figs. 16, 17 and 18, and including a pressure device by which the end flaps of the carton are pressed against the ends of the cores successively.

Fig. 19^a represents a sectional view, in a horizontal plane, (see line 19^a—19^a of Fig. 18) through a carton whose end flaps have been folded against the end of the core and are about to be subjected to pressure to set them.

Fig. 20 represents a top plan view of the pressure device in coöperative relation to a core, the carton as shown by Fig. 19^a being omitted.

Fig. 21 represents an elevation of the mechanism by which the cartons are stripped from the cores successively, preparatory to being charged. The point of view of this figure is the reverse of Fig. 1.

Fig. 21^a represents a sectional view, in a horizontal plane, of a carton at an intermediate stage of being stripped from its core, and includes the stripper acting thereon.

Fig. 22 is an elevation similar to Fig. 21 excepting that the stripper is shown as having stripped a carton from its core.

Fig. 22^a represents an elevation (the view being from left to right with reference to Fig. 22) of the holder, hereinafter termed a righting device, into which the cartons are moved by the stripper as they are stripped from the cores.

Figs. 23, 24 and 25 represent elevations of the righting device in successive positions, Fig. 25 showing a carton as having been moved to an upright position with its closed end at the bottom and as having been deposited in the holder or carrier that supports it during the charging operation.

Fig. 26 represents an elevation similar to Fig. 25, on a larger scale, and includes a device that folds down one of the flaps at the upper end of the carton after the carton has been charged.

Fig. 27 represents an elevation, partly in section, of the assemblage shown by Fig. 26, the view being from left to right with reference to Fig. 26.

Fig. 28 is an elevation, similar to Fig. 27, of the carrier that holds the carton for

charging, and includes the device by which two of the flaps at the upper end of the carton are folded down after the carton has been charged and before it is removed from 5 charging position.

Fig. 29 is a view similar to Fig. 28, with the addition of the mechanism that operates the folding devices,—the carton and its carrier having moved a short distance to the 10 left from charging position. See arrow D, Fig. 3.

Fig. 30 represents an elevation, partly in broken lines, of the operating mechanism within the range of line 30—30 of Fig. 26.

Fig. 31 is an elevation, from the same point of view as Fig. 26 and from the opposite point of view with reference to Fig. 1, of the carrier that carries the charged cartons from charging position to the second paste-applying device and thence to the 20 point of delivery.

Fig. 32 represents a plan view, in diagrammatic form, of the stationary devices that act on the sealing flaps at the top of 25 the carton while the latter is being transferred from charging position to the point of delivery. This figure is intended to be read in conjunction with Fig. 3, as it illustrates elements that are purposely omitted 30 from Fig. 3.

Fig. 33 represents an elevation, partly in section, of the paste-applying rolls included in Fig. 31 and of a device that sustains one of the flaps of the carton during the paste- 35 applying operation. In this figure the paste-applying rolls are shown as being at the limit of their paste-applying traverse.

Fig. 34 is a view similar to Fig. 33 excepting that the paste-applying rolls are 40 shown at the beginning of their paste-applying traverse, the direction of such traverse being indicated by an arrow.

Fig. 35 is a view similar to Fig. 34 excepting that the flap-sustaining device is in 45 a lower position.

Fig. 36 is an elevation, partly in section, of the paste-applying device from the point of view indicated by line 36—36 of Fig. 31.

Fig. 36^a is an elevation, partly in section, 50 of the one-way roll-driving elements of the paste-applying device.

Fig. 37 is an elevation, from the same point of view as Fig. 31, of the elements that close and seal the carton after the latter leaves the paste-applying device shown by Figs. 31 to 36. The direction of view of Fig. 37 is the reverse of that of Fig. 1.

Fig. 38 is an elevation of the carton-sealing device included in Fig. 37, the point of 60 view being the same, but the sealing device being in the act of operating upon the carton.

Fig. 39 is an elevation similar to Fig. 38 excepting that the sealing device and carton

have both been moved to the right, the 65 carton having been transferred from its carrier to a stationary delivery table by a transferring device.

Fig. 40 is an elevation, partly in section, of the carton-charging elements within the 70 range of line 40—40 of Fig. 3.

Fig. 41 represents an elevation, partly in section, on a larger scale, of the controlling elements included in Fig. 40.

Fig. 42 is a vertical cross section through 75 the charging device. See line 42—42 of Fig. 40.

Fig. 43 is an elevation, partly in section, of the mechanism that controls the delivery of charging material from the charging 80 device. The point of view is the same as that of Figs. 21 and 22, and Fig. 43 is to be read in conjunction with Figs. 21 and 22 because the stripper is the element that acts, through the medium of the empty carton, to 85 permit the delivery of charging material only when an empty carton is placed in position to receive such material.

Fig. 44 represents an elevation of some of the controlling elements included in Fig. 90 43, in another position.

Fig. 45 is a top plan view of the elements at the left of Fig. 43, and includes a carton in broken lines.

Fig. 46 is a view similar to Fig. 44, showing 95 the controlling elements in another position.

The same reference characters indicate the same parts wherever they occur.

The flat carton blanks α are arranged in 100 a stack and the stack rests upon the movable bottom or support 50 (Figs. 1 to 6) of an otherwise stationary holder. The stationary elements of the holder include four upright walls 51, and a stationary bottom 105 section 52. The latter is provided with notches 52' into which projections 50' of the movable bottom extend, as shown by Figs. 3 and 5. The stationary section 52 and the projections 50' prevent the marginal 110 portion of the bottom carton blank from sagging when the movable section is retracted, as shown by Figs. 4 and 5, preparatory to feeding such blank. Movable section 50 is provided with slightly raised elements 50^x of about the same thickness as, or slightly less thickness than, that of each blank α . These raised elements, when moved from right to left, abut against the right-hand edge of the blank at the bottom of the 120 stack and push such blanks through a crack 53 in the holder. As the leading edge of the blank leaves the crack 53 it passes between and is caught by co-operative feed rolls 54. Spur gears 55 transmit rotation from one 125 roll to the other. The lower gear receives rotation from spur gears 56, 57. The upper feed roll 54 is pressed downward by helical

compression springs such as that indicated at 58 in Fig. 4.

The movable bottom 50 is reciprocated to feed the bottom blank as aforesaid, by 5 eccentrics such as that indicated at 59 in Figs. 4 and 6, and it is sustained by rollers 60. Eccentrics 59 and gear 57 are affixed to shaft 61. The movable bottom 50 is provided with confronting lugs 62 that straddle 10 and coact with the eccentrics.

As the blank leaves the feed rolls 54 it rests upon a horizontally movable table 63 (Figs. 3, 4 and 7). The direction of the first movement of the blank is indicated by 15 arrow A in Fig. 3. After the blank has been fed to table 63 its next feed movement is that indicated by arrow B. (Figs. 3 and 7). Table 63 is provided with an abutment 64 and with a flange 65. One marginal portion 20 of the blank goes under the flange, as shown by Fig. 7, and when the table is moved in the direction of arrow B the blank is fed positively by the abutment 64. A spring plunger 66 is arranged to bear downwardly 25 upon the blank to keep the latter firmly seated on table 63, but, when the table is wholly retracted as shown by Fig. 7, this plunger is raised slightly to enable the blank to be fed on to the table by feed rolls 54. 30 Plunger 66 is normally depressed by a helical compression spring 67 and is provided with a roll 68. A cam bar 69 is affixed to table 63 so as to move forward and back, and is arranged to lift the plunger when the 35 table is in blank-receiving position. When the blank has been fed to the desired position on table 63 its leading edge engages a stop 70 (Fig. 7). Table 63 is then moved in the direction of arrow B. For this purpose it is provided with a gear rack 71. This 40 rack is engaged by gear segment 72 on operating lever 73. The link 74 connects lever 73 with cam lever 75. Lever 75 has a cam roll 76 that coacts with cam 77 on shaft 78. 45 Table 63 feeds the blank over continuously rotating feed roll 79, and the blank is taken from the table by the conjoint action of roll 79 and a pair of feed segments 80 when the latter reach the position shown 50 by Fig. 14. These feed segments are affixed to a continuously rotating shaft 81. These continuously driven elements 79 and 80 receive rotation from shaft 78 through a train of gearing that need not be described in 55 detail, but it is illustrated by Fig. 2.

Shaft 81 carries paste-applying devices by which portions of the blank are coated with paste as they pass over the roll 79. Before describing the machine further I 60 will describe the blank for which the machine is organized. Referring to Fig. 4^a, the blank comprises side walls x' , x^2 , x^3 and x^4 , a side flap x^5 , and two sets of end flaps. End flaps a' , a^2 , a^3 and a^4 are folded prior 65 to the filling of the carton, to provide the

bottom; and end flaps b' , b^2 , b^3 and b^4 are folded after the carton has been filled, to close it. Flaps a^2 and a^4 and marginal portion x^6 of x' are pasted prior to being folded, and flaps b^2 , b^4 are likewise pasted prior to 70 being folded, but after the carton has been filled. The blank is preferably scored, as indicated by dotted lines, to facilitate the several folding operations.

The paste-applying mechanism now about 75 to be described is that for pasting flaps a^2 and a^4 and marginal portion x^6 . Referring to Fig. 7, shaft 81 carries paste pads 82, 83 and 84 of soft material such as rubber. The paste-carrying surfaces of these pads 80 are slightly beyond the peripheral surfaces of feed segments 80. A pasting roll 85 is arranged to be engaged by the pads, but is out of range of the feeders 80. This roll occupies a paste reservoir 86, and transfers 85 paste from the latter to the said pads. It is driven continuously by the train of gears that drives the feeders 80. Pad 82 is arranged to engage marginal portion x^6 (Fig. 4^a), and pads 83 and 84 are arranged to 90 engage flaps a^2 and a^4 respectively, of the carton blank.

Feed table 63 has only to advance the blank far enough to place marginal portion 95 x^6 of the blank in position to be caught by pad 82 and roll 79, and when the blank is taken by the last-named elements the feed table is returned to blank-receiving position (Fig. 7) for the next blank coming from the stack.

Strippers 87 are provided for stripping the blank from the paste pads. These strippers are alike in structure and operation, and a description of one will suffice for all. Each stripper is in the form of a rod and is 100 arranged radially with relation to shaft 81 and extends through its respective paste pad. The inner end of the stripper has pivot connection with an arm 88. There are three sets of strippers, and their arms 88 are 105 fixed upon three rockshafts 90 respectively. Each rockshaft is provided with a cam arm 89 and each such arm is provided with a roll 91. These rolls follow each other and traverse a stationary cam 92. The rolls are 110 pressed against the cam by helical compression springs 93 coiled about the strippers. Cam 92 is so formed as to permit the strippers to be retracted by their springs while the pads are carrying paste from rolls 85 to 115 120 the blank, and to impart stripping action as each stripper passes beyond roll 79.

The pasted blank traverses a stationary feed table 94 and passes over the continuously driven feed roll 95. Feed segments 96 125 carried by a continuously driven shaft 97 coact with roll 95 to feed the blank until its leading edge reaches stops 98 (Fig. 11). These stops are at the lower end of an inclined table 99. Shortly before the blank 130

reaches stops 98 it is registered sidewise by converging guides 100 affixed to table 99. The position of the blank, when it reaches stops 98, is represented by dotted lines in Fig. 11. It will be observed that the blank bridges a gap 101 in table 99, said table being in reality made in two sections separated from each other. Stops 98 are so located in relation to gap 101 as to cause portion α^3 of each blank to register with the gap. The purpose of gap 101 is to permit the passage of the cores upon which the blank is folded and formed prior to being filled. The cores just referred to are indicated at 102. In the present instance there are four such cores (Figs. 2 and 14) and they are carried by arms or spokes 103 affixed to a turret consisting of a rotatable slot-wheel 104. The cores as the turret is indexed pass downwardly successively through gap 101, and in doing so they depress portion α^3 of each blank. The blank is thus folded around three sides of the core, as shown by Fig. 11, and the core has a period of dwell 25 when it reaches the station or position where it is shown in cross section in this figure. As the core reaches this position portion α^3 of the blank is clamped against it by a presser 105; and as soon as this presser has been brought to bear, another presser 106 is moved toward the core to press portion α^4 of the blank against the core. While the blank is clamped by presser 106, a folding device 107 is operated to fold flap α^5 over the upper left-hand edge of the core, as shown by Fig. 12. This fold having been made, presser 105 is retracted from the path of the core and flap α^5 is folded down so that its pasted marginal portion α^6 will overlap flap α^5 . The folding down of α^5 is performed by a folding device 108. As soon as α^5 has been folded so as to confine flap α^5 , folding device 107 is retracted and a presser 109 (Figs. 14 and 15) is brought to bear upon the marginal portion α^6 to cause the latter to adhere to flap α^5 . In order to relieve the core from the downward stress of presser 109, a counter presser 110 is arranged to press upwardly against the bottom of the core. Pressers 109 and 110 remain in the position shown by Fig. 15 for a sufficient period to enable the paste to adhere to flap α^5 , and while they are in that position presser 106 and folding device 108 are retracted from the core. In due time the pressers 109 and 110 are retracted from the path of the cores, and the latter are rotated through 90 degrees of a revolution to take away the partly folded carton and to bring the next empty core to its first position of use. Each core is moved to four successive stations.

The turret or slot-wheel 104 that carries the cores is loosely mounted upon continuously driven shaft 111, and is provided with

four radial slots 112. A pin gear 113 (Fig. 2) mounted upon shaft 114 is provided with a roller 115 that traverses the slots 112 to rotate the slot-wheel intermittently by steps of ninety degrees each. The rim of the slot-wheel is concaved in well known manner to receive the periphery of the pin gear so that the slot-wheel will be locked during its period of dwell. 70

Presser 105 (Figs. 11 and 12) is affixed to rockshaft 116. An arm 117, likewise affixed to said rockshaft, is connected by a link 118 with cam lever 119. The fulcrum of this lever is at 120. A roll 121 on the lever contacts with cam 122 affixed to continuously rotating shaft 111. A helical tension spring 123 moves the lever to retract presser 105, and cam 122 actuates the lever to move the presser to operative position (Fig. 10). 75

Presser 106 is carried by a bell-crank lever 124. This lever is loosely mounted upon rockshaft 125. Lever 124 is oscillated by cam 126 (Fig. 1) on shaft 78. Folding device 107 is carried by an arm 127. This arm is affixed to rockshaft 125. The rockshaft is 80 oscillated by a cam arm 128 affixed to it, and this cam arm is actuated by cam 129 (Fig. 1) on shaft 78. 85

Folding device 108 (Figs. 12 and 13) is affixed to rockshaft 130. A spur gear 131 95 is affixed to this rockshaft is oscillated by a gear segment 132 on cam lever 133. The fulcrum stud of this lever is at 134, and the operating cam 135 therefor is affixed to the shaft 78. (See Fig. 1). 100

Pressers 109 and 110 are carried by arms 136, and these arms are mounted upon a common fulcrum rod 137. Each arm 136 is provided with a pair of toggle members 138. The fixed pivot of each pair of toggle members is indicated at 139, and the middle pin or joint of each pair is indicated at 140. The pins 140 of the corresponding upper and lower toggle members are connected by links 141, and the lower pins are provided with 110 cam rolls, as indicated at 142. Cams 143 (Fig. 1) coact with rolls 142 to actuate the pressers in unison. 115

Referring to Fig. 16^a, the flaps α^1 , α^2 , α^3 and α^4 of the blank project beyond the end 120 of the core, and as the core is about to reach its dwelling position or second station at the bottom of its circle of travel, flap α^3 strikes a stationary deflector 144 (Figs. 16 to 19) and is thereby folded against the end of the core 120 as indicated by an arrow in Fig. 16^a. While the core remains in its lowest dwelling position, as shown by Figs. 17, 18 and 19, flap α^1 that is opposite α^3 is folded over upon the latter by a movable folding device 145. 125 This device is carried by a bell-crank lever 146 and is operated by a link 147, cam lever 148 and cam 149. This cam is carried by shaft 78. (See Fig. 1). Folding device 145 remains in the position shown by Fig. 18, 130

and shown by dotted lines in Fig. 19, until the core starts to move to the next dwelling position, and the flaps a' and a^3 traverse the surface 150 of member 144 and are thereby held in their folded position while flap a^2 is being folded down to confine them. Flap a^2 , which is then at the upper side of the carton, passes under and is engaged by a stationary rail 151 that deflects it downwardly as shown by Fig. 16^b. The folding of flap a^2 occurs before flap a' leaves retaining element 150, and thus serves to prolong the confinement of flaps a' and a^3 . The inner surface of flap a^2 , having been coated with paste, ultimately adheres to flaps a' and a^3 when it is pressed against the latter as hereinafter explained. When flap a^2 has been folded, flap a^4 engages a stationary rail 152 and is folded inwardly upon flap a^2 as shown by Fig. 16^c. The latter figure represents the condition of the carton when the core is about half way between line 16^b—16^b (Fig. 16) and the next dwelling position or station of the core. Rails 151 and 152 are not relied upon to exert any great pressure against the end of the core, but their function is merely to fold the flaps a^2 and a^4 one upon another so that the flaps will be in position to be set by the pressure device now about to be described.

The pressure device is indicated at 153 and is located at the third station. It is connected to a reciprocatory head 154 by pins or bolts 155 and is normally pressed forward by helical compression springs 156 surrounding said bolts. The head 154 is provided with parallel shanks 157 that slide in bearings 158. A toggle member 159 is pivotally connected to the head and is pivotally connected at 160 to another toggle member 161. The anchor pivot of the toggle members is at 162. Toggle member 161 has a roller that occupies a slot 163 in a sliding bar 164. This bar is arranged to slide in a guide 165 and is provided with a cam roll 166. A cam 167 affixed to continuously rotating shaft 111 reciprocates bar 164 to operate the toggle member, and the pressure device 153 is thus brought to bear against the folded flaps on the end of the core, through the cushioning springs 156. The stress against the core is sustained by an abutment 168 (Fig. 3).

The next dwelling position or fourth station of the core, after it is moved from registration with the end presser 153, is at the top of the circle of travel. (See Figs. 2, 15, 21 and 22). In the latter position the core stands in registration with a stripper that moves the carton endwise from the core in the direction indicated by arrow C in Figs. 3 and 21. This stripper transfers the carton to a righting device that turns the carton so that the closed end will be at the bottom, preparatory to feeding in the granular or

other material with which the carton is to be filled.

The stripper includes a sliding carriage 169 and two co-operative claws 170 (Fig. 21^a) carried thereby. The carriage is arranged to slide horizontally on guide rods 171. The claws 170 are affixed to vertical rockshafts 172, and the latter are mounted in suitable bearings in the carriage. The upper ends of the rockshafts are provided with fingers 173 that engage stops 174 when the carriage is retracted preparatory to stripping, to move the claws 170 toward each other. Each core is provided with grooves 175 to receive the rear ends of the claws, as shown by Fig. 21^a. When the carriage is retracted in the direction opposite arrow C the claws are deflected away from each other by the carton then in register and the claws are moved toward each other, as stated, after they have passed the carton. Then when the carriage moves in the direction of arrow C, the rear ends of the claws abut against the edges of flaps b' , b^3 as shown by Fig. 21^a.

The carriage is reciprocated by an endless chain 176. This chain passes over sprocket wheels 177. One of the sprocket wheels is affixed to a shaft 178 (Figs. 1, 2 and 3), and this shaft is provided with a pinion 179 that meshes with a vertically movable rack 180. The lower portion of the rack has gear teeth 95 that coact with a gear segment 181. This segment is mounted upon a pivot stud 182 and is provided with a cam roll 183 that coacts with a cam 184 (Fig. 21) carried by shaft 111. Fig. 22 shows the stripper in the act of depositing the carton on the righting device, and Figs. 1 and 3 show the stripper in the same position but do not include the carton. Fig. 21 shows the stripper about to transfer the carton from the core. 105

The righting device includes a tilting table 185 upon which the carton rests after it leaves the core. This table is provided with two hinged side plates 186 (see Fig. 22^a) the hinges of which are indicated at 187. The outer edges of the plates are bent toward each other to provide flanges 188 to confine the carton. Arms 189 are affixed to plates 186 respectively, and their free ends are connected by a helical tension spring 190 that tends to swing the plates away from each other. As the righting device approaches carton-receiving position the plates 186 are closed as shown by Fig. 22^a, and for this purpose the device is provided with toggle members 191, 192, 192. The middle member 191 is mounted upon a pivot pin 193, and its free ends are connected with arms 189 respectively by the members 192 and suitable pivot connections. When the righting device is about to reach carton-receiving position, toggle member 191 (then out of alignment with members 192) strikes a stop 194 and is placed 110 115 120 125

in the position shown by Fig. 22^a by slight farther downward movement of the device. This operation moves the several pivot pins of the toggle members slightly past "dead center", where they are held by stop pin 195.

When the righting device is in the position shown by Fig. 22 it is in registration with the core, and the stripper moves the carton into the inclosure formed by elements 10 185, 186, 186, 188, 188. These elements are proportioned so as to clamp the carton sufficiently to keep the latter from slipping.

The carton holder shown by Fig. 22^a is carried by a swinging arm 196 from the position shown by Figs. 22 and 23 to the position shown by Figs. 25, 26 and 27. In the latter position the carton stands in an upright position with its closed end at the bottom. Arm 196 is affixed to rockshaft 197, 20 and the latter is provided with a pinion 198 (Fig. 2). A rack bar 199 coacts with this pinion, and its upper end is provided with a roll (not shown) that coacts with a path cam 200. This cam is carried by a continuously driven shaft 201.

The righting device is connected to the arm 196 by a pivot member 202 and has a tilting motion independent of the angular movement of the arm. For this purpose the 30 righting device is provided with an arm 203 (Fig. 26), and said arm is provided with a cam roll 204 that traverses a cam groove 205. This cam groove is formed in a fixture 206. The cam groove is so formed as to right the 35 carton more rapidly than would be the case if the angular movement of the swinging arm were utilized for this purpose, and the carton is thus placed in an upright position before the swinging arm reaches an upright 40 position. After the carton reaches an upright position as shown by Fig. 24, it moves bodily without angular movement to the position shown by Figs. 25, 26, and is thus placed under and in registration with a spout 207 from which the granular or other material is discharged into the carton.

Each carton, on reaching the latter position, is received by a holder that carries it away after it has been filled. In the present 50 instance there are four such holders, and they are mounted upon a turret or rotary carrier, ninety degrees from each other. Each such holder comprises a bottom or support 208, an upright wall 209, and hook-shaped arms 210. The latter are shown best by Fig. 3. These arms are open, as shown at the top of Fig. 3, when the carton is delivered to them, but as soon as the carton reaches the 55 position shown by Figs. 25 and 26 the arms are closed to embrace it. Simultaneously with the delivery of the carton to the arms 210 the hinged plates 186 of the righting device are opened. Such opening movement is brought about by a fixture 211 (Fig. 22^a) 60 that stands in the path of the outer end of

one of the toggle members 192. The effect of the fixture 211 is to move the toggle members from "dead center", and spring 190 then completes the opening movement of the plates 186. The flanges 188 are thus carried away from each other beyond the sides of the carton so that the righting device may be retracted without the carton.

The carton-charging mechanism is hereinafter described, and for present purposes 75 it will be sufficient to state that the required quantity of material M is discharged through the spout 207 while the carton is embraced by arms 210. Assuming that the carton has been charged as shown by Fig. 80 27, flaps b' and b^a are folded down, in the order stated, before the carton is taken away. The folding of these flaps is accomplished by tilting devices 212. These devices are affixed respectively to rockshafts 213. The 85 rockshafts are mounted in suitable fixtures and are provided with pinions 214 (Fig. 30). These pinions are oscillated by gear segments 215. Each gear segment is affixed to a rockshaft 216, and each rockshaft is provided with an operating arm 217. Connecting rods 218 connect the arms respectively with cam levers 219. These levers are mounted upon fulcrum members 220 and are normally raised by helical tension springs 95 221. Cam rolls 222 mounted on the cam levers coact respectively with cams 223. These cams are affixed to continuously rotating shaft 111. As soon as flap b' has been folded down as shown by Fig. 28, flap 100 b^a is folded down over it, cams 223 being set one ahead of the other to fold the flaps in such order.

The carton is thus substantially closed before it is taken away from charging position, although it is not sealed, flaps b^a and b⁴ being left in upright position so that they may be laid back to receive paste as herein-after explained.

Referring to Fig. 3, arrow D represents 110 the charging position of the carton, and from this position the carton is carried in the direction indicated by the arrow. The four holders by which the cartons are held for charging are mounted upon a carrier 115 224 that rotates around a vertical axis. This carrier has four radial grooves 225 and is rotated step by step by roller 226 on a continuously driven carrier 227. (See Figs. 3 and 31). The closing and opening of hooked 120 arms 210 are accomplished by a grooved cam 228 (Fig. 3). There are two pairs of arms for each carton, and they are affixed to two rockshafts 229. (Fig. 37). Each rockshaft has at its lower end an operating 125 arm 230, and these arms extend toward each other and embrace a pin 231 carried by a sliding bar 232. The four bars are arranged radially and their inner ends are provided with rolls 233 that traverse the cam 228. 130

Cam 228 does not remain stationary at all times and does not rotate continuously. It has a short oscillatory motion for the purpose of closing the arms of one holder and 5 for the purpose of opening the arms of another holder while the carrier 224 is stationary. The cam is affixed to a vertical rockshaft 234. (Fig. 37). The upper end of this shaft is provided with an operating 10 arm 235. A double-jointed connection 236 connects the arm with a connecting rod 237. (Figs. 3 and 37). This rod extends to a cam lever 238 with which it is connected by a double-jointed connection 239. The 15 fulcrum member of the lever is indicated at 240. A cam roll 241 (Fig. 1) coacts with a grooved cam 242 on continuously rotating shaft 233.

While the filled carton is being transferred from position D (Fig. 3) to its next dwelling position at E (Fig. 32) ninety degrees distant, flaps b^2 and b^4 are laid back, away from each other, preparatory to having paste applied to them. This operation 20 is performed by stationary rails 243 and 244 that are arranged to deflect the flaps as the carton moves. While this is in progress flaps b' and b^3 are retained in their folded position by a substantially semicircular 25 stationary rail 245 under which the carton travels. Rails 243 and 244 deflect the outlying flaps to a substantially horizontal plane and the latter flaps are thus enabled to pass under a paste carrier 246. Flap b^4 30 is laid back upon a plate 247 that is carried by the carton holder, and flap b^2 on reaching paste-receiving position at E overlies a plate 248. The latter plate is movable up and down and occupies its lower position, 35 as shown by Fig. 31, when the carton approaches; but after the carton has reached position E, plate 248 is raised to the position indicated by dotted lines in Fig. 31, to support flap b^2 against the action of the 40 paste-applying means hereinafter described. For this purpose the plate 248 is mounted upon the upper end of a vertically movable bar 249. The bar is normally depressed by a helical compression spring 250. A cam roll 45 251 at the lower end of the bar rides upon an annular cam 252 carried by continuously rotating disk 227.

This paste-applying device includes a reciprocating carriage 253 that slides on 50 horizontal guide rods 254. While the carton is at position E the upper surfaces of flaps b' , b^2 , b^3 and b^4 are traversed by a brush 255, and any particles that may be upon the flaps are thus removed before the paste is 55 applied. This brush is carried by the paste carrier 246 and precedes the paste-applying rolls 256. There are two paste applying rolls, one of which engages flap b^2 and the other of which engages flap b^4 . These rolls 60 are mounted in carriage 253 and they have

rolling contact with the paste-feeding roll 257.

The arrows in Figs. 31 and 34 indicate the direction in which the carriage moves to apply paste. A connecting rod 258 (Fig. 1) 70 connects the carriage with a cam lever 259. The fulcrum pin of this lever is indicated at 260. The lever is provided with a cam roll 261 that coacts with a grooved cam 262 carried by shaft 233. The paste-applying device occupies the position represented by solid lines in Fig. 31 when the carton reaches position E, and is then moved to the position represented by dotted lines in that figure. The paste-applying rolls 256 are separated 80 from each other as shown by Fig. 36 so as to apply paste only to flaps b^2 and b^4 . They have rolling contact with the flaps and are rotated positively in one direction by gearing shown in Figs. 1, 3 and 36^a. A stationary horizontal rack 263 coacts with a spur gear 264. This gear and a similar gear 265 are mounted upon the shaft that carries the rolls 256. Gear 265 is affixed to the shaft and is provided with a ratchet wheel 282 85 (Fig. 36^a), but gear 264 is loosely mounted upon the shaft and is provided with pawls 283 that drive the ratchet wheel to apply paste and merely click over the teeth of the ratchet wheel when the paste-applying device is being 90 retracted. The paste rolls are thus driven only when the carriage moves in one direction. The function of the gear 265 is to transmit rotation to the feed roll 257, and for this purpose the latter is provided with 95 a gear 266.

As soon as the flaps have been pasted, flap-supporting plate 248 is permitted to drop and the carton then advances to the next stopping position, indicated at F in Fig. 3. 100 During this transfer of the carton the semicircular rail 245 continues to hold down flaps b' and b^3 , and flaps b^2 and b^4 are folded upwardly and toward each other and then downwardly one upon the other by stationary rails 267 and 268. The flaps b^2 and b^4 105 have a natural tendency to spring back to their former upright positions, although this tendency is diminished to some extent. Nevertheless, it is sufficient to cause them to spring up approximately 45 degrees as soon as they are released by the paste-applying rolls. This springing up is sufficient to put them in position to be caught by the stationary rails 267 and 268. Rail 267 is in 110 advance of rail 268 and acts first to lay flap b^4 upon flaps b' and b^3 as shown by Fig. 32. In due course flap b^2 reaches rail 268 and is thereby folded to the angular position shown by Fig. 37. The folding of flap b^2 is completed by rollers 269. These rollers are carried by carriage 270 that is arranged to slide on horizontal guide rods 271. The carriage is reciprocated by mechanism that includes 115 a connecting rod 272, cam lever 273, and cam 120 274.

274. When the carton reaches dwelling position F in register with rollers 269, the latter are moving in the direction indicated by the arrow in Fig. 37 and the flap b^2 is thus 5 folded down upon flap b^4 immediately upon the arrival of the carton at this position. As soon as the rollers 269 have traversed flap b^2 they are moved in the opposite direction as indicated by arrows in Fig. 38 and are thus 10 caused to traverse the flap twice before the flap is released. This gives the paste sufficient opportunity to adhere before the carton is removed from its holder. While the rollers are making their return traverse 15 upon the flap, arms 210 are retracted by movement of cam 228, and by the time the rollers have left the carton the latter is free to be removed from the holder. The direction of its removal is indicated by arrow F 20 in Fig. 3, and by the arrows in Figs. 38 and 39.

The removal of the now closed and sealed carton is effected by a pusher that moves horizontally. This pusher includes fingers 275 and a sliding bar 276 for carrying them. A connecting rod 277 connects the bar with a cam lever 278. This lever is actuated by a 25 grooved cam 279 on shaft 233. As the carton moves from its movable support 208 it 30 passes on to a stationary table 280 along which it is fed by the pusher. During this feeding-out movement the carton passes under spring plates 281 that are arranged to keep flap b^2 pressed upon the flap under it, 35 and the pasted flaps are thus more firmly set. What becomes of the cartons after they are placed upon the table 280 is immaterial so far as present purposes are concerned. They may be taken away manually, or they may be 40 pushed into an inclined chute or on to an endless conveyer.

The charging of the cartons at position D (Fig. 3) is determined, in the present instance, according to the bulk rather than the 45 weight of material, because the charging operation can be effected more rapidly on this basis than if it were necessary to weigh it. The mechanism that measures the material is controlled automatically so that there will 50 be no discharge of material unless a carton is in position to receive the material. The controlling mechanism is arranged to be actuated by the cartons as the latter are being transferred from the cores 102 to the 55 righting device. Fig. 45 represents a plan view of the free end of a core and of the carton-engaging arm 284 by which the discharge is controlled. Arm 284 normally extends into the path traversed by the carton, its normal position being represented 60 by solid lines in Fig. 45, but when it is displaced by the carton it is moved to the position indicated by dotted lines. This arm is affixed to a vertical rockshaft 285. A 65 helical torsion spring 286 turns the rock-

shaft to place the arm in its normal position. The upper end of the rockshaft is provided with an arm 287, and this arm has pivotal connection with a bar 288. The bar slides in a guide 289, and when it is in its 70 normal position its right-hand end lies in the path of movement of a feeler 290. The feeler is affixed to a rockshaft 291, and the rockshaft is provided with an operating arm 292. A jointed eccentric rod comprising 75 two members 293 and 294 oscillates arm 292, provided movement of the latter is not prevented by coaction of feeler 290 with bar 289. The two members of the jointed eccentric rod are pivotally connected with each 80 other by a pivot pin 295, and member 293 is pivotally connected to arm 292 by a pin 296. Member 294 is fitted to an eccentric 297 carried by continuously rotating shaft 201. The force of gravity normally keeps 85 the members 293 and 294 in abutting relation as shown by Figs. 43 and 44; but if the bar 288 is not retracted from the path of the feeler when the latter descends, continued movement of the eccentric rod causes 90 the member 293 to swing about pivot pin 296. This results in upward movement of member 294, and such upward movement is transmitted to a vertically movable drop 298. If the drop is not lifted the feeder 95 hereinafter described will discharge material M, but if the drop is lifted in consequence of non-displacement of arm 284 the feeder will not discharge.

Referring to Figs. 2, 3, 40 and 42, the 100 feeder comprises a substantially cylindric casing 300. This casing is stationary and is provided with two rotary heads 301 and 302. These heads are carried by a shaft 303 that is rotated intermittently through clutch 105 mechanism hereinafter described. Casing 300 has an opening 304 at the top to receive material M from any convenient source above. The material M is conducted to the casing 300 by a chute 305. The interior of 110 the casing is divided, in the present instance, into four compartments by four radial blades 306. These blades are affixed to head 301 and they extend into radial grooves formed in head 302. The latter 115 head is adjustable toward and from head 301 to vary the cubic area of the several compartments, so that the bulk of material discharged to each carton may be determined according to the capacity of the carton. For this purpose shaft 303 is provided with a screw-thread 307, and a nut 308 is arranged thereon. The nut is provided with a peripheral groove 309, and the groove is occupied by a block 310 carried by head 120 302. Turning the nut relatively to the shaft moves the head 302 toward or from the head 301, according to the direction in which the nut is turned.

Casing 300 is provided with a discharge 125

opening 311 to which the granular material is moved by the blades 306. The spout 207 hereinbefore mentioned is fastened to the lower side of casing 300 and conducts the material M into the cartons.

A disk 312 is loosely mounted on shaft 303 and is provided with four radial grooves 313. This disk is rotated intermittently in one direction by roller 314 on disk 315. The latter is carried by continuously rotating shaft 201. The hub of disk 312 constitutes one member of a toothed clutch, and the other member of such clutch is a sliding collar 315. This collar is movable endwise on shaft 303 but is connected to the shaft by a spline 316. The collar is formed with a peripheral groove 317 into which a shipper 318 extends. The shipper is affixed to a rod 319. An intermediate portion of this rod is turned down to a smaller diameter, as shown by Fig. 41, to provide a shoulder 320. This shoulder is the element that coacts with the drop 298 hereinbefore mentioned. As shown by Fig. 41, the members 312 and 315 are clutched one to the other to transmit rotation from 312 to the rotary feeder, and the collar 315 is maintained in clutched position by the drop 298. A helical compression spring 321 is coiled about shipper rod 319 and tends to move said rod to unclutch collar 315. Consequently, when through coaction of feeler 290 and bar 288 drop 298 is lifted, shipper rod 319 is released so that spring 321 can unclutch collar 315. Eccentric 297 is arranged to lift the drop during the interval roller 314 is actuating disk 312; but if a carton has been placed in charging position, its transfer to the righting device retracts bar 288 so that drop 298 will permit the feeder to partake of the rotary movement of disk 312.

Assuming that the feeder has been thrown out of action by non-displacement of arm 284, clutch collar 315 will be automatically restored to clutching position in the course of the next revolution of shaft 201, by a cam 322. This cam is affixed to shaft 201 and actuates a lever 323. This lever has pivotal connection with a collar 324 that is affixed to shipper rod 319.

As long as the cartons follow each other in regular order without any omission, clutch collar 315 will remain connected with disk 312, and clutch-connecting lever 323 will remain out of contact with its cam.

I claim:

1. A machine for forming and charging cartons, comprising mechanism arranged to fold carton blanks into carton form, said mechanism including a series of forming cores arranged so that their axes of movement are horizontal, a series of blank-folding devices for acting successively upon the carton blanks, and means for moving said cores successively into coactive relation with

said devices successively, whereby a plurality of carton blanks may be caused to undergo the carton-forming operation simultaneously, a charging spout arranged to discharge granular material, mechanism arranged to transfer the empty cartons from said cores successively to upright charge-receiving position in register with said spout, and a carton holder for holding the cartons in said charge-receiving position. 70 75

2. A machine for forming and charging cartons, comprising mechanism arranged to fold a carton blank into carton form with its axis horizontal, a charging spout arranged to discharge granular material, a movable holder arranged to hold a carton in charge-receiving position in register with said spout, mechanism arranged to transfer the empty carton from said blank-folding mechanism to said carton holder, said transferring mechanism being arranged to turn the carton to upright position, and means arranged to move said holder to and from register with said spout. 80 85

3. In a machine for making and charging cartons, a carrier arranged to rotate on a horizontal axis, a plurality of rectangular cores carried by said carrier and arranged with their axes parallel to said axis, one end of each said core being exposed, means arranged to coact with said cores successively to form carton blanks into cartons with end-forming flaps of such blanks against said ends of the cores, a spout arranged to discharge granular material, carrying means 90 provided with a series of supports each adapted to support a carton, said carrying means being arranged to move said supports into register successively with said spout, and means arranged to transfer the empty 95 cartons from said cores to said supports, said transferring means being arranged to turn the cartons so as to cause said end-forming flaps to rest on said supports. 100 105

4. In a machine for making and charging cartons, a plurality of horizontal cores, a carrier therefor, said cores being arranged in a series, means for moving said carrier intermittently to give said cores a series of predetermined positions of rest, means arranged 110 to coöperate with said cores to form cartons thereon, a plurality of carton holders arranged to hold the cartons upright, means arranged to transfer the cartons from said cores, successively, to said holders, means arranged 115 to move said holders successively into register with said transferring means, said transferring means being arranged to turn the cartons to upright position, and means arranged to discharge uniform quantities of granular material into the cartons supported by said holders. 120 125

5. In a machine for making and charging cartons, a plurality of horizontal cores, a carrier therefor, said cores being arranged in 130

- a series, means for moving said carrier intermittently to give said cores a series of predetermined positions of rest, means arranged to coöperate with said cores to form cartons 5 thereon, a plurality of carton holders arranged to hold the cartons upright, means arranged to strip the cartons from said cores successively, means arranged to receive the cartons from said stripping means and transfer them to said holders, said transferring means being arranged to turn the cartons to upright position, means arranged to move said holders successively into register with said transferring means, and means arranged 10 to discharge uniform quantities of granular material into the cartons supported by said holders. 15 6. In a machine for making and charging cartons, means arranged to feed carton blanks one by one, means arranged to apply paste to one or more bottom-forming flaps of each blank, a plurality of rectangular cores, a rotary carrier for said cores, the axes of said cores and carrier being horizontal, means arranged to rotate said carrier step by step, means arranged to coact with said cores to form the blanks on said cores with the bottom-forming flaps against the ends of the cores, a plurality of carton holders each having a bottom support, a rotary carrier for said holders, means arranged to transfer the empty cartons successively from said cores to said holders, said transferring means being arranged to turn the cartons upright so that 20 the bottom-forming flaps will rest on the bottom supports of said holders, and means arranged to discharge uniform quantities of granular material into the cartons supported by said holders. 25 7. In combination, charging mechanism adapted to measure and deliver predetermined quantities, successively, of charging material, means arranged to move a plurality of empty cartons, one by one, from horizontal to upright charge-receiving position relatively to said charging mechanism, and controlling means arranged normally to prevent the charging operation of said charging mechanism, said controlling means being arranged to be controlled by the cartons, as the latter move from horizontal to upright charge-receiving position, to enable said charging mechanism to operate. 30 8. In combination, charging mechanism adapted to measure and deliver predetermined quantities, successively, of charging material, disconnectible continuously operated driving means arranged to operate said charging mechanism, means arranged to move a plurality of empty cartons, one by one, from horizontal to upright charge-receiving position relatively to said charging mechanism, power-driven mechanism arranged normally to disconnect said driving means at a predetermined point in the cycle 35 of operations, and controlling means arranged to be successively actuated by the empty cartons to prevent said power-driven mechanism from disconnecting said driving means from said charging mechanism. 70 9. In a carton-making machine, a rectangular core, means arranged to coact with said core to bend a carton blank into tubular form around said core with two marginal portions of the blank lapped on one face of the core, means arranged to carry said core to and from coöperative relation with said blank-bending means, and pressure-exerting means arranged to coact with said core to press said lapped portions of the blank against each other, the latter said means including two coöperative pressure members and mechanism arranged to move them in unison to and from operative positions against opposite sides of the tubular blank. 75 10. In a carton-making machine, a rectangular core, means arranged to coact with said core to bend a carton blank into tubular form around said core with two marginal portions of the blank lapped on one longitudinal face of the core, means arranged to carry said core to and from coöperative relation with said blank-bending means, a pair of pressure-exerting jaws, one of which is arranged to press the lapped marginal portions of the blank against said longitudinal face of the core, and the other of which is arranged to sustain the core against such pressure, and means arranged to move said jaws in unison to and from operative position. 80 11. In a machine for making cartons, a rotary carrier, means for rotating said carrier step by step, a series of rectangular cores affixed to said carrier with their axes 85 parallel to the axis of said carrier, one end of each said core being exposed, means arranged to coact with said cores to fold carton blanks into carton form upon said cores with end forming flaps of such blanks 90 against said exposed ends of the cores, a pressure device arranged to press such flaps against the ends of the cores, a carrier for said pressure device movable in lines parallel to the axes of said cores, cushioning 95 means arranged to transmit flap-pressing movement from the latter said carrier to said pressure device, and means arranged to move said carrier to cause such flap-pressing movement. 100 12. In a machine for making and charging cartons, a rotary carrier, a plurality of cores carried thereby, means arranged to turn said carrier step by step, means arranged to coact with said cores successively 105 to fold carton blanks on said cores, a series of movable supports each adapted to support a carton and each provided with co-operative jaws arranged to hold the carton in place on the support, means arranged to 110 130

transfer the empty cartons from said cores to said supports successively, means arranged to open and close said jaws to receive and release the cartons, and a spout arranged to discharge granular material into the cartons on said supports.

13. In a machine for making and charging cartons, a rotary carrier, a plurality of cores carried thereby, means arranged to turn said carrier step by step, means arranged to coact with said cores successively to fold carton blanks on said cores, a series of movable supports each adapted to support a carton and each provided with co-operative jaws arranged to hold the carton in place on the support, means arranged to transfer the empty cartons from said cores to said supports successively, said transfer means including co-operative jaws arranged to clamp a carton, means arranged to open and close said clamping jaws, means arranged to open and close the first said jaws, and a spout arranged to discharge granular material into the cartons on said supports.
14. A machine for making cartons, comprising a rotatable turret arranged on a horizontal axis and having a plurality of spaced cores parallel with its axis, means for feeding blanks successively into the path of said cores, means for folding the blanks about said cores successively, and means for stripping the folded cartons successively from the cores and setting them in upright charge-receiving position.
15. A machine for making cartons, comprising a rotatable turret arranged on a horizontal axis and having a plurality of spaced cores parallel with its axis, means for imparting a step - by - step rotation to said turret, continuously rotating means for delivering spaced blanks successively into the path of said cores, and means arranged to fold and clamp the cartons against the cores.
16. A machine for making cartons, comprising a rotatable turret arranged on a horizontal axis and having a plurality of spaced cores parallel with its axis, means for imparting a step - by - step rotation to said turret, a table having a recess to permit the passage therethrough of said cores, means on said table for positioning the blanks in relation to said recess, means for sustaining

a pile of blanks, continuously rotating means for pasting and for feeding the blanks at spaced intervals to said table and blank-positioning means, and means located below said table for folding the blank about the core.

17. A machine for making cartons, comprising a rotatable turret arranged on a horizontal axis and having a plurality of spaced cores parallel with its axis, means for imparting a step-by-step rotation to said turret to locate each core at different successive stations, means for feeding pasted blanks into the path of said cores, means located at one station for folding the sides of the blank about each core, means for folding the end flaps of the blank about the end of the core, an end presser located at a succeeding station and movable longitudinally of the core to press the end flaps against the end of each core and means located at a next succeeding station for stripping the folded blank from each core.

18. A machine for making and charging cartons, comprising a turret rotatable about a horizontal axis and having a plurality of spaced cores parallel with said axis, instrumentalities for folding blanks and closing the flaps at one end thereof about said cores successively, a turret movable about a vertical axis and having spaced upright carton holders, and instrumentalities for stripping the folded cartons from said cores successively and transferring them in upright position to said holders successively.

19. A machine for making and charging cartons, comprising a turret rotatable about a horizontal axis and having a plurality of spaced cores parallel with said axis, instrumentalities for folding blanks and closing the flaps at one end thereof about said cores successively, a turret movable about a vertical axis and having spaced upright carton holders, instrumentalities for stripping the folded cartons from said cores successively and transferring them in upright position to said holders successively, means for closing the top end flaps of the cartons while held by said holders, and means for effecting the discharge of said cartons from said holders.

In testimony whereof I have affixed my signature.

JOSEPH FOSSEL.
